(57) **CLAIM**

The ornamental design for a trim reveal extrusion, as shown and described.

DESCRIPTION

FIG. 1 is a perspective view of a trim reveal extrusion showing my new design.

FIG. 2 is a cross-sectional end view thereof; and, FIG. 3 is an end elevational view thereof, showing the trim reveal extrusion in an environmental use.

The broken lines in FIG. 3 illustrate environmental subject-matter only and form no part of the claimed design.

In FIG. 1, the trim reveal extrusion is shown with a symbolic break in its length. The appearance of any portion of the trim reveal extrusion between the jagged break lines forms no part of the claimed design.
